HIGHWAY TRAFFIC GUARD

Eugene V. Camp, Atlanta, Ga.

Application January 2, 1942, Serial No. 425,445

15 Claims. (Cl. 256—13.1)

1

This invention relates to highway guard rails, and more particularly to a new and improved safety device of the plate type.

Heretofore certain structures technically classified as "full floating" have been proposed, these embodying essentially a supporting post, a circular annular spring attached thereto, and an impact member associated with said spring as by means of a clip, an alleged free movement of the impact member in relation to its supporting means being thereby provided.

In operation, certain deficiencies have been observed in structures of this design due to the fact that upon impact the rail tends to be forced sharply inwardly and to partially simulate the contour of the circular spring members at the posts, the result being to impart appreciable jolt and jar to an impacting vehicle as it glides by these points, and even in some instances to hang the vehicle up at such locations. In other cases the rail member may tend to freeze under impact instead of sliding in its intended manner, the result then being to reduce considerably the effective resiliency of the assembly, and even to rupture the rail because of its inability to function in its intended manner in cooperation with the other elements.

An object of the instant invention is to provide a traffic guard the impact member of which has a pivoted guiding clip attached to its supporting bracket and in effect pivots adjacent the posts during operation, thereby reducing potential sharp bumps at these points and providing a smooth gliding approach thereto under impact.

Another object is to provide a guard rail in which the inherent resiliency of both impact member and supporting springs or brackets is fully taken advantage of during operation.

A still further object is to provide economy of manufacture and simplicity of construction in a device of the instant type.

Another object is to provide efficiency of function and economy of maintenance in a highway guard rail.

These and other objects made apparent during the further progress of this specification are effected by the instant invention, a full and complete understanding of which is facilitated by reference to the drawing, in which:

Fig. 1 is a front view of an assembled guard rail embracing my invention;

Fig. 2 is an enlarged fragmentary top plan view at one of the intermediate posts suggested in Fig. 1;

Fig. 3 is a view of the structure disclosed in Fig. 2, as same operates under impact;

2

Fig. 4 is a horizontal sectional view of the structure shown in Fig. 1, same being taken through the approximate center thereof;

Fig. 5 is a front view of the structure of Fig. 2 taken along the line 5—5 looking in the direction of the arrows;

Fig. 6 is a vertical sectional view of the structure of Fig. 2 taken through the approximate center thereof;

Fig. 7 is a plan view of one of the blanks from which may be formed the spring connector elements of my guard rail;

Fig. 8 is an alternate form of one of the clip members which I employ, together with its associated rail element; and

Fig. 9 is a plan view of an alternate form of blank which may be employed in forming appropriate connector elements for my guard rail structure.

Referring now to the drawing, it will be seen that the instant device contemplates a series of posts or supports 10 to which are attached curved spring elements 11 through bolts 12 and nuts 13. Elements 11 may be formed from a blank of suitable metal and provided at their ends with a series of prongs 14 (Fig. 7) which are in turn carried around through a suitable arc to form a series of staggered fingers 15 (Figs. 5 and 6).

An alternate form of blank is suggested in Fig. 9 in which prongs 16 are substantially rectangular in form, the resulting finger structure in either case being substantially identical from a functional standpoint.

A sheet metal plate member 17 is attached to springs 11 through an intermediate clip 18, said clip comprising a flat strip of metal having its ends carried around as at 19 and 20 for the purpose of providing channels in which element 17 may ride, it being contemplated that the distance between 19 and 20 and the face of clip 18 shall be such as to permit a snug but free engagement of the rail with the clip.

A series of indentations 21 are struck in the face of clip 18 as by means of pressure applied to a suitable die, said indentations being so spaced as to register with the fingers of element 11. A pair of bolt or pintle-like members 22 (Figs. 2 and 6) is then passed downwardly through alternate fingers of spring 11 and interlocking indentations of clip 18, with the result that the clip becomes in effect pivotally mounted with the connector at these points. As stated heretofore, the impact member 17 is then passed through the clips at the posts.

The ends of given assemblies may be provided with coil springs 23 operating on bolts 24 in such

manner as to place the entire assembly in longitudinal tension; and suitable anchoring and bracing elements such as 25 may likewise be employed.

To facilitate erection as when impact member 17 is brought to the field in long rolls or coils, as is often the case, a modified form of clip 18 may be employed, such a structure being disclosed in Fig. 8 and contemplating the making of such element in two pieces 18a and 18b instead of one, it being apparent that when this is done one-half of the clip may be put in place, the impact member reeled out and associated with said half, and the other portion of the clip then being brought into engagement with the opposite edge of the rail, this arrangement making it possible to erect long assemblies without difficulties that otherwise might exist in "threading" sections of rail through unitary clips previously in place.

From the foregoing description it is believed that the operation of my device will be clear to those skilled in the art, it being apparent that when a vehicle hits the traffic guard (see Fig. 3) a pivotal motion is at once set up between the impact member and the spring connector, the arm nearest the impacting force tending to turn inwardly and the opposite arm acting as a fulcrum around which turns a section of the rail and its associated clip, there being thereby effected a smooth gliding approach at the supports instead of a rigid bump. The impacting vehicle is thereby enabled to pass successive posts with a minimum of damage until such time as speed is reduced and the driver given an opportunity to again get the car under control. The entire operation is a smooth and natural one in which the inherent resiliency of all members of the assembly perform to their best advantage.

Further, the various elements of the instant device may be easily stamped out, thereby guaranteeing economy in manufacture; and replacement of damaged parts is likewise efficient and simple.

In the light of the foregoing, it is submitted that the instant traffic guard represents a novel and meritorious contribution to the guard rail art, and as such, warrants an interpretation of the appended claims fairly in keeping with such contribution.

I claim:

1. In a traffic guard of the character described, a series of supports, curved spring brackets mounted on said supports, a clip pivotally united with the front portions of said brackets, and an impact member carried by said clip in sliding relationship therewith.

2. In a traffic guard of the character described, a series of supports, spring brackets mounted on said supports, a clip pivotally united with the front portions of said brackets, and an impact member carried by said clip in sliding relationship therewith.

3. In a traffic guard of the character described, a series of supports, spring brackets mounted on said supports, a clip pivotally united with the front portions of said brackets, and a flexible resilient impact member carried by said clip in sliding relationship therewith.

4. In a traffic guard of the character described, a series of supports, curved spring brackets mounted on said supports, a clip pivotally united with the front portions of said brackets, and a flexible resilient impact member carried by said clip in sliding relationship therewith.

5. In a traffic guard of the character described,

a series of supports, spring brackets mounted on said supports, the front portions of said brackets being formed to provide a series of staggered fingers, clips adjacent the front faces of said brackets, curved indentations in said clips positioned in interlacing relationship with the openings of said fingers, pintle members passed through said openings and indentations, thereby pivotally mounting the clips with the spring brackets, and an impact member carried by the clips in sliding relationship therewith.

6. In a traffic guard of the character described, a series of supports, curved spring brackets mounted on said supports, the front portions of said brackets being formed to provide a series of staggered circular fingers, clips adjacent the front faces of said brackets, curved indentations in said clips, said indentations having generally vertically extending apertures therein and being positioned in interlacing relationship with the openings of said fingers, pintle members passed through said openings and indentations, thereby pivotally mounting the clips with the spring brackets, and an impact member carried by the clips in sliding relationship therewith.

7. In a traffic guard of the character described, a series of supports, spring brackets mounted on said supports, the front portions of said brackets being formed to provide a series of staggered pintle bearings, clips adjacent the front faces of said brackets, curved indentations in said clips positioned in interlacing relationship with the openings of said pintle bearings, pintle members passed through said openings and indentations, thereby pivotally mounting the clips with the spring brackets, and an impact member carried by the clips in sliding relationship therewith.

8. In a traffic guard of the character described, a series of supports, spring brackets mounted on said supports, the front portions of said brackets being formed to provide a series of staggered pintle bearings, clips adjacent the front faces of said brackets, curved indentations in said clips positioned in interlacing relationship with the openings of said pintle bearings, pintle members passed through said openings and indentations, thereby pivotally mounting the clips with the spring brackets, and a sheet metal impact member carried by the clips in sliding relationship therewith.

9. In a traffic guard of the character described, a series of supports, spring brackets mounted on said supports, the front portions of said brackets being formed to provide a series of staggered pintle bearings, clips adjacent the front faces of said brackets, curved indentations in said clips positioned in interlacing relationship with the openings of said pintle bearings, pintle members passed through said openings and indentations, thereby pivotally mounting the clips with the spring brackets, and an impact member carried by the clips in sliding relationship therewith.

10. In a traffic guard of the character described, a series of supports, spring brackets mounted on said supports, the front portions of said brackets being formed to provide a series of staggered pintle bearings, clips adjacent the front faces of said brackets, said clips having separable upper and lower portions, curved indentations in said clips positioned in interlacing relationship with the openings of said pintle bearings, pintle members passed through said openings and indentations, thereby pivotally mounting the clips with the spring brackets, and

an impact member carried by the clips in sliding relationship therewith.

11. In a traffic guard of the character described, a series of supports, spring brackets mounted on said supports, the front portions of said brackets being formed to provide a series of staggered pintle bearings, said pintle bearings being of uniform width throughout, clips adjacent the front faces of said brackets, curved indentations in said clips positioned in interlacing relationship with the openings of said pintle bearings, pintle members passed through said openings and indentations, thereby pivotally mounting the clips with the spring brackets, and an impact member carried by the clips in sliding relationship therewith.

12. In a traffic guard of the character described, a series of supports, spring brackets mounted on said supports, the front portions of said brackets being formed to provide a series of staggered pintle bearings, said pintle bearings having points of maximum width at their bases and narrowing at their ends, clips adjacent the front faces of said brackets, curved indentations in said clips positioned in interlacing relationship with the openings of said pintle bearings, pintle members passed through said openings and indentations, thereby pivotally mounting the clips with the brackets, and an impact member carried by the clips in sliding relationship therewith.

13. A highway guard rail fitting comprising a curved spring bracket having a rear or support engaging surface and oppositely disposed wing-like front portions, said front portions being formed to provide a series of staggered pintle bearings at the ends thereof, a clip associated with said front portions, curved indentations in

said clip positioned in registering relationship with the openings of said pintle bearings, and pintle members passed through said openings and indentations, thereby pivotally mounting the clip with the spring bracket.

14. A highway guard rail fitting comprising a spring bracket having a rear or support engaging surface and oppositely disposed wing-like front portions, a series of staggered pintle bearings formed in the ends of said front portions, a clip adjacent the front portions of said brackets, curved indentations in said clip positioned in interlacing relationship with the openings of said pintle bearings, and means for pivotally mounting the clip with the spring bracket.

15. A highway guard rail fitting comprising a ring-like spring bracket having a rear or post engaging surface and oppositely disposed wing-like front portions, a series of pintle bearings formed in opposite ends of said front portions, and a clip pivotally mounted with said bearings adjacent the front of said bracket.
